UNITED STATES PATENT OFFICE

LOUIS H. STOMPS, OF FAIRFIELD, ALABAMA

DUST-GUARD-WEDGE RETAINER

Application filed November 18, 1926. Serial No. 149,086.

This invention relates to improved means for retaining or holding in place the so-called dust guard wedge which is adapted to close the opening through which the dust guard 5 of a railway car journal box is inserted. The invention will be apparent from the following specification when read in connection with the accompanying drawings and the features of novelty will be pointed out with particularity in the appended claim. In the drawings—

Fig. 1 is a vertical section through the journal box of a railway car truck having a dust guard wedge retainer embodying my invention;

Fig. 2 is a section on line 2—2 of Fig. 1;

Fig. 3 is a plan of Fig. 1;

Fig. 4 is an enlarged detail section on line 4—4 of Fig. 3.

Referring in detail to the drawings, 10 represents the shell or body of a journal box which in the embodiment illustrated is formed integrally at one extremity of a truck side frame, the compression member 25 of which is shown at 12. The journal box will be provided with the usual journals which form no part of the present invention and, hence, are not shown in detail. The axle 14 is provided with the usual journal 30 portion 16 and with a slightly enlarged portion 18 around which is fitted a dust guard 20 usually made of wood, fibre or similar comparatively soft or non-abrasive material which will not injure or cut the axle as it 35 rotates in use. The function of the dust guard as its name implies is to prevent the entrance of dust and other foreign matter into the interior of the journal box. The journal box is formed at its inner side with 40 flanges 22 and 24 spaced apart sufficiently far to form a pocket 26 to accommodate the dust guard. Openings 28 and 30 are formed in the flanges 22 and 24 of such size that limited relative movement between the journal box and the axle can be had without in-

terference of the parts. The pocket 26 has an open mouth at the top as indicated at 32 to permit the initial insertion of the dust guard. My invention aims particularly to provide improved means for closing the 50 mouth 32 so that foreign matter cannot enter the box through said mouth. To these ends, I provide an improved dust guard retainer wedge 34 which in the embodiment illustrated consists of a strip of wood substantially 55 square in cross-section which is driven or wedged through aligned holes 36 and 38 formed in upstanding ears 40 and 41 formed integrally on the journal box adjacent the narrow ends of the pocket 26. After the 60 retainer has been driven into place, I drive nails or dowels 42 through the same as indicated in Figs. 3 and 4 so as to prevent the retainer from being displaced. It is clear that the retainer 34 cannot be jogged out of 65 place whether or not its fit in the holes 36 and 38 is a tight or snug one. It is preferable in a device of this sort to have a fairly tight fit between the retainer 34 and the holes or sockets which receive it. Such a tight fit 70 would probably hold it for a considerable length of time but due to the fact that railway car parts are subject to extreme temperatures and further to the constant vibration, it is apparent that in time the wood 75 might shrink or perhaps might wear and thus work the retainer loose. Such wear or loosening cannot cause the retainer to be displaced when the locking dowels 42 are provided as described.

I contemplate such modifications as would suggest this to those skilled in the art such as the substitution of screws, bolts or spring dowel pins for the nails shown in the drawing.

What I claim is:—

An axle journal box of the character described having a dust guard pocket formed therein with an open mouth at the top, the walls of said pocket extending above the top 90

of the box, the end walls of said pocket having rectangular perforations therein and a wooden member of rectangular cross-section in wedged engagement with said perforations and closing said mouth and dowels driven in said wooden member to prevent dislodgement thereof upon shrinkage of the wood.

In witness whereof, I have hereunto signed
10 my name.

LOUIS H. STOMPS.
